INVENTOR

UNITED STATES PATENT OFFICE.

OVE L. GAMMELGAARD, OF ATTLEBORO, MASSACHUSETTS, ASSIGNOR TO
ELECTRIC CHAIN COMPANY, A CORPORATION OF MAINE.

BRACELET.

No. 836,109.

Specification of Letters Patent.

Patented Nov. 20, 1906.

Application filed May 24, 1906. Serial No. 318,459. (Model.)

To all whom it may concern:

Be it known that I, OVE L. GAMMELGAARD, a citizen of the United States, residing at Attleboro, in the county of Bristol and State of Massachusetts, have invented certain new and useful Improvements in Bracelets, of which the following is a specification, reference being had therein to the accompanying drawings.

10 My invention relates to bracelets, and is particularly adapted to that class of expandible bracelets comprising crossed arms working upon the lazy-tongs principle, of which the structure shown in United States Patent No. 782,188 is an example, which type is not adapted to receive an ornament or ornamental mounting intermediate its length, since to fix the free extremities of a pair of the centrally-pivoted arms would prevent 20 any expansion of the adjacent bracelet parts.

My invention, however, is not limited to any particular form of bracelet, its object being to join the bracelet-circle to an ornamental setting intermediate its length without 25 the use of solder, whose employment in this art has the well-known disadvantage of annealing the metal adjacent the soldered joint.

30 A further object is to provide a novel solderless means of mounting a removable ornament in the setting. Finally, it is purposed to so mount a setting or ornament in a lazy-tongs bracelet as to permit not only longitudinal or expansive movement of the bracelet 35 from the ornament, but a transverse or rocking movement of the bracelet-body in relation thereto.

To the above ends, essentially, my invention consists in the novel construction herein-40 after described, and illustrated in the accompanying drawings, wherein—

45 Figure 1 is a front elevation of a bracelet of the lazy-tongs type embodying my invention; Fig. 2, a rear elevation of the section of the bracelet adjacent the ornament; Figs. 3 and 4, plan and transverse sectional views, of the pivoted link with shell removed; Figs. 5 and 6, front and transverse sectional views, respectively, of an inner link-shell; Fig. 7, a 50 front elevation of an outer link-shell; Fig. 8, a section of the ornament on line 1 1 of Fig. 2; Figs. 9 and 10, a plan and transverse section of one of the pivot-plates; Figs. 11 and 12,

similar views of the pivot-plate covering; Fig. 13, a side elevation of the ring member; 55 Fig. 14, a section on line 2 2 of Fig. 1; and Fig. 15, a fragmentary view of the bracelet, showing the bracelet-body tilted in relation to the ornament.

Like reference-letters indicate like parts 60 throughout the views.

In the embodiment of my invention herein shown, A represents a lazy-tongs bracelet-body, comprising the series of arms a, centrally pivoted to the series of arms b, and the 65 series of intermediate spring-cases c. D is an ornamental member which may or may not embrace a stone or gem. In the structure shown this member comprises a circular wall d, provided upon its upper retracted portion 70 with an inturned flange d' and upon its lower margin with an inturned flange d'', the former to embrace a stone or gem E and the latter to retain the margins of a bearing-plate F for the gem, and a guard-plate G outside the 75 bearing-plate. The setting-wall d is provided with a series of openings h, preferably three, at diametrically opposite points in each side of the wall. The setting d is provided with thin lateral extensions or plates I, 80 (shown in detail in Fig. 9,) provided with lateral lugs i and a central opening i''. The lugs i are inserted through the openings h of the setting-wall d and are riveted or swaged therein. Over each plate I is swaged an ornamental shell J, such as shown in Fig. 11, provided with a recess j, positioned to register with the opening i'' of the plate I. Pivoted to the plates I, on each side thereof, are links K, each comprising an inner plate k 90 with end perforations k' k'', over one side of which is swaged an ornamental shell k''. A pivot-pin or rivet L, as shown in Fig. 14, passes through the openings i'', j, and k'', thereby pivoting the links K at their inner ends to 95 the plates I. The outer ends of the links K are pivoted by rivets passing through the openings k'' to the ends of the adjacent arms a.

It will be noted that the shells J and k'' entirely conceal the rivet-heads and present fine-metal exterior. The parts are united without solder, and not only is longitudinal expansion of the bracelet afforded, but a transverse swing thereof is permitted in relation to the ornament, as shown in Fig. 15.

When a stone is not used in the ornamental body D, the bearing-plate F is omitted.

What I claim is—

1. The combination with the crossed arms and setting member of a lazy-tongs bracelet, of lateral plates upon the setting member, and links pivoted to the plates and to the adjacent crossed arms.
2. The combination with the crossed arms and setting member of a lazy-tongs bracelet, of lateral plates upon the setting member, and a pair of links pivoted at their inner ends upon the opposite sides of each plate and pivotedally connected at their outer ends with the adjacent crossed arms.
3. The combination with the crossed arms and setting member of a lazy-tongs bracelet, of pivotal means connecting the setting member and crossed arms for permitting an inclination of the crossed arms in relation to the setting member.

4. An ornamental unit for bracelets, the same comprising a circular wall provided with openings in its side, a flange upon its bottom, a guard-plate engaged by the flange 25 and plate provided with lugs adapted to enter the openings in the circular wall.

5. An ornamental unit for bracelets the same comprising a circular wall provided with openings in its side a flange upon its bot- 30 tom a flange upon its top a guard-plate engaged by the bottom flange, an ornament engaged by the upper flange and plates provided with lugs adapted to enter the openings in the circular wall. 35

In testimony whereof I have affixed my signature in presence of two witnesses.

OVE L. GAMMELGAARD.

Witnesses:

HORATIO E. BELLOW,
FRED IRVIN COZZENS.
